DESIGN FOR AN ANIMAL BOOT

Bancroft W. Henderson, Montclair, N. J.

Application May 24, 1939, Serial No. 85,177

Term of patent 14 years

To all whom it may concern:

Be it known that I, Bancroft W. Henderson, a citizen of the United States, residing at Montclair, in the county of Essex and State of New Jersey, have invented a new, original, and ornamental Design for an Animal Boot, of which the following is a specification, reference being had to the accompanying drawing, forming part thereof in which:

Fig. 1 is a rear perspective view of the animal boot of the invention, and Fig. 2 is a side elevational view of the boot looking at the right side thereof, showing my new design.

I claim:

The ornamental design for an animal boot, as shown.

BANCROFT W. HENDERSON.
